Sumatra Trading Company, Inc., New York, N.Y., a
corporation of New York

Filed Aug. 24, 1962, Ser. No. 219,235

4 Claims. (Cl. 67—7.1)

This invention relates to an improved cigarette lighter, and in particular relates to an improved cigarette lighter mechanism providing for positive control of a fuel valve by operation of the main actuating member of the lighter. One object of the invention is to provide an improved cigarette lighter mechanism of the above-described type, wherein the control means for the valve is concealed within an internal compartment of the lighter, together with simple means coupling the actuating means for the valve to the external actuating member for the mechanism as a whole.

Another object of the invention is to provide valve control mechanisms of the above type, which can be controlled in response to various movements of the main actuating member.

In accordance with preferred embodiments of the invention, the cigarette lighter includes a casing divided into a lower fuel tank and an upper compartment having a top wall. The compartment has a bottom opening at its front communicating with the fuel tank, and the lighter also has a fuel valve including a vertical plunger in the compartment at its front and receiving fuel through said opening. Such valve mechanism is described in detail in my copending application, entitled Cigarette Lighter Fuel Control Mechanism, filed on August 24, 1962, Serial No. 219,236. The plunger is movable between an upper valve opening position and a lower valve closing position. The top wall has a top wall front opening overlying the valve for flow out of the casing of fuel vapors or gas from the valve.

A first lever extends longitudinally in the compartment and is laterally mounted intermediate its ends to the casing. The front end of the first lever is coupled to the plunger for movement thereof in the opposite sense to movement of the rear end of the first lever. Spring means couple the rear end of the first lever and the casing and urge the rear end upwardly so as to maintain the valve normally closed.

The lighter further comprises a snuffer shaped and sized to block the top wall front opening and thereby block raising of the plunger, as well as lateral pivot means mounting the snuffer on the casing above the top wall for movement of the snuffer between top wall front opening blocking and unblocking positions.

A second lever, which is the main actuating lever for the lighter, is mounted on the casing above the top wall for movement between first and second positions. The second lever and the snuffer are coupled for movement of the snuffer to blocking position by movement of the second lever to first position, and to unblocking position by movement of the second lever to second position.

As an important feature of the invention, the top wall has a rear opening, and the lighter has means including a member extending through the top wall rear opening coupling the second lever and the first lever so that movement of the second lever to second position causes lowering of the rear end of the first lever. The second lever is normally biased to its first position.

In accordance with one preferred embodiment of the invention, the actuating member is mounted so as to control the action of the snuffer by longitudinal movement. This facilitates actuation of the snuffer. In accordance with this embodiment, cam means are employed

2

to couple the second lever through an extension through the top wall rear opening of the first lever. In another embodiment of the invention, a third lever extends through the top wall opening that couples the first and second levers.

Other objects and advantages of the invention will become apparent from the following description, in conjunction with the annexed drawing, in which preferred embodiments of the invention are disclosed.

10 In the drawing:

FIG. 1 is a vertical longitudinal section of a first embodiment of the invention, showing the parts in their normal position in which the lighter is not operating;

15 FIG. 2 is a fragmentary view similar to FIG. 1, showing the lighter when it has been placed into operation;

FIG. 3 is a perspective view of the operating lever which directly controls the fuel valve;

20 FIG. 4 is a longitudinal vertical section of a second embodiment of the invention, showing the lighter in inactive condition;

FIG. 5 is a fragmentary view similar to FIG. 5, showing the lighter placed into operation; and

25 FIG. 6 is an exploded perspective view of the operating levers which directly control the operation of the fuel valve.

First Embodiment

FIG. 1 shows a longitudinally elongated cigarette lighter casing C of rectangular shape having a top wall

30 21. Partition wall 22, parallel to and near wall 21, divides casing C into a lower fuel compartment or fuel tank F and an upper compartment D. Compartment D has a bottom opening 23 at its front communicating with fuel tank F. Fuel valve E including vertical plunger 24 is mounted in compartment D at its front, overlying opening 23 and receiving fuel vapors or gas from tank F through said opening 23. Said valve E may be of any suitable type, such as that shown in my aforesaid patent application filed on the same day as this. Plunger 24 is movable between an upper valve opening position wherein fuel flows through the top of valve E and a lower valve closing position. Top wall 21 has a top wall front opening 15 overlying plunger 24 for flow out of the top of casing C of fuel vapors from valve E.

40 45 First lever A extends longitudinally in compartment D. Said lever A may be formed from any suitable metal bar or strap material by a simple punching operation. Lever A has a rear flat portion 24 and an upstanding lateral flange 3 connected to the rear edge of said lever portion 24. Lateral flange 3 depends from the front edge of lever portion 24 and connects at its lower end with a forwardly upwardly inclined lever portion 6. Said lever portion 6 connects at its front end with a forwardly extending lever front portion 25 which is bifurcated at its front end to form legs 1. The inclined portion 6 has an aperture 7. The front end of lever portion 24 is provided with parallel, laterally opposing, depending side ears 4 having apertures 4a.

50 55 In assembly, lever A is received within compartment D with pivot pin 4b extending turnably through the apertures 4a of ears 4 and fixed to the side walls of casing C by any suitable means (not shown). Front holder 17 extends vertically above casing C and also extends downwardly through any suitable opening in top wall 21 and further downwardly slidably through opening 7 of lever portion 6. Top wall 21 has a rear opening 16 through which flange 3 extends. Accordingly, the main portion of flange 3 is normally located above casing C. Flange 3 serves as a transverse extension of the first lever A.

60 65 Further as mounted in compartment D, the bifurcated legs 1 of front lever portion 25 extend around either side of a portion 9 of reduced diameter of plunger B, so that

70 75

Further as mounted in compartment D, the bifurcated legs 1 of front lever portion 25 extend around either side of a portion 9 of reduced diameter of plunger B, so that

plunger B moves in the opposite sense to movement of the rear end of first lever A. Spring 5 extends between the rear end portion 24 of lever A, rearwardly of pivot 4b, and the top wall 22 of tank F, so as to urge the rear end of first lever A upwardly and thereby normally maintain valve E closed.

Snuffer 19 is mounted by lateral pivot 19a on any appropriate element 27 fixed to casing upper wall 21 rearwardly of plunger B. Said snuffer 19 is shown in its blocking position in FIG. 1 wherein it blocks top wall opening 15 and thereby blocks complete raising of plunger B. In this position, snuffer 19 may be considered as extending generally horizontally from its pivot 19a. In the unblocking position of snuffer 19, shown in FIG. 2, it may be considered as extending generally vertically from its pivot 19a, and it unblocks the top front opening 15 and permits raising of plunger B.

In order to control operation of snuffer 19 and first lever A, there is provided a main actuating lever or second lever 12. Said lever 12 has a top wall 13 with a concave central portion 13a to provide a finger accommodating hollow, a depending rear wall 30, side walls 31 which connect to top wall 13 and rear wall 30 and which extend forwardly of top wall 13, and an open bottom. The side walls 31 are connected at their front ends to the outer sides of snuffer 19, by means of pivot 31a. Said pivot 31a is located above, in vertical alignment with and spaced from pivot 19a in the normal condition of the parts shown in FIG. 1. The lower peripheral edge of lever 12 is normally spaced above top wall 21.

The upper end of cam lever 8 is connected by pivot 8a between side walls 31 of second lever 12, adjacent the rear thereof. Said cam lever 8 extends downwardly forwardly from pivot 8a. Elongated bracket 14 is fixedly mounted upon the upper face of wall 21. Said bracket 14 has a raised rear portion 14a with a longitudinally elongated slot receiving the tapered lower end 8b of lever 8, so as to serve as a stop to forward movement thereof, as shown in FIG. 1, while permitting some rearward movement thereof as shown in FIG. 2.

Lever 12 is forwardly and rearwardly movable, and its rear end portion can also be moved upwardly and downwardly. Spring 20 connected between the front end 14b of bracket 14 and pivot 8a normally maintains lever 12 in its position of FIG. 1. In operation, the finger may be placed upon the hollow 13a of lever 12 and the lever may be pulled rearwardly, while at the same time its rear end is also depressed somewhat, to the position shown in FIG. 2. This actuating movement of lever 12 may be considered as generally in the direction of the arrow 32, this arrow extending rearwardly and somewhat downwardly. The pivot connection 31a between lever 12 and snuffer 19 causes clockwise motion, as taken in FIGS. 1 and 2, of snuffer 19 about its pivot 19a, to unblocking position. This particular actuating mechanism was convenient because it produces a satisfactory mechanical advantage.

As a further feature of the invention, the upper end of lever extension 3 engages against the lower cam surface 8c of cam lever 8, which thereby controls the action of lever A. In the position of FIG. 1, said cam surface 8c is downwardly forwardly inclined, and the upper edge of lever extension 3 engages against said surface 8c near the rear thereof. In the actuating movement of lever 12, as the result of the engagement of the lower end portion 8b of lever 8 against the slot in bracket portion 14a, and as the result of the downward movement of the rear portion of lever 12, the cam surface 8c is turned so that it assumes the generally horizontal position shown in FIG. 2. At the same time, the upper edge of lever extension 3 slides to the front of the cam surface 8c. Further, by reason of the lowering of the rear portion of lever 12, and the resulting lowering of cam surface 8c, lever extension 3 is depressed, against the action of spring 5, thereby raising plunger B. Upon release of lever 12 and its return

to its normal position, by reason of the action of spring 20, spring 5 raises the rear end of lever A and maintains the upper edge of lever extension 3 against the cam surface 8c. The operation of the lighter will be readily apparent from the detailed description above. When it is desired to use the lighter, lever 12 is moved backwardly and at the same time depressed, thereby raising the snuffer 19, optionally striking a conventional spark by means of a conventional mechanism (not shown), and lowers the rear end of lever A, which thereby raises plunger B to opening position, permitting fuel vapor or gas to rise through opening 15 above the casing for ignition. When lever 12 is released, the parts return to their normal inactive position of FIG. 1.

Second Embodiment

The chief difference in the two embodiments resides in the manner of mounting of the second lever (actuating lever), and in a change in the manner of coupling the second lever and the first lever.

The parts of the second embodiment which are the same as those in the first embodiment are designated by the same reference characters and are not described in detail. Lever AA, shown in detail in FIG. 6, is similar to lever A, except that the rear lever portion 240 is shorter in length, and the rear lever extension 3 is omitted in the second embodiment. Furthermore, the spring 50 is located closer to the pivot ears 4 in the second embodiment than in the first embodiment.

Lever 120 is of similar shape to lever 12, except that the dished upper portion 13a is optionally omitted in the second embodiment. Also, various contours of the levers are slightly different.

In the second embodiment, the side walls 310 of lever 120 are connected by lateral pivot 310a, adjacent their rear, to any appropriate upper casing extension 99. The front end of lever 120 is connected to the rear of snuffer 99 by means of pivot 190a, other conventional details being omitted. However, it will be apparent without extended description that when the front portion of lever 120 is depressed, or moved in the counterclockwise direction around the axis of pivot 310a, as taken in FIGS. 5 and 6, snuffer 19 is moved to its unblocking position of FIG. 5.

In the second embodiment, a flat third lever 98 is provided, this lever 98 having its rear end rolled downwardly and under into a bead 97 which is mounted upon lateral pivot 96, this pivot 96 being attached by any suitable means to the side walls of casing C within compartment DD. Said lever 98 extends over and abuts the rear end of lever AA. The front ends of lever 98 is provided with an upstanding transverse extension 30 which extends upwardly through rear hole 160 of top wall 210 of casing C. However, as will be apparent from inspection of the drawing, said rear hole 160, while located rearwardly of the top wall front opening, is somewhat spaced from the rear of the casing, in order to accommodate the transverse extension 300. The upper end of said transverse extension 300 abuts the top wall 130 of lever 120, forwardly of pivot 310a.

In the second embodiment, the spring 50 serves both normally to maintain lever AA in valve closing position, but also serves normally to maintain lever 120 in its normal position. In operation, when lever 120 is depressed, in the direction of arrow 320, snuffer 19 is raised, and at the same time the lever extension 300 is lowered, thereby engaging against the rear end portion of lever AA when depressing it, with corresponding raising of plunger B to valve opening position. Upon release of lever 120, spring 5 returns the parts to their normal position of FIG. 4.

While I have disclosed preferred embodiments of my invention, and have indicated various changes, omissions and additions which can be made therein, it will be apparent that various other changes, omissions and ad-

ditions may be made in the invention without departing from the scope and spirit thereof.

What is claimed is:

1. Cigarette lighter mechanism comprising:

a casing having a longitudinal axis and divided into a lower fuel tank and upper compartment having a top wall, said compartment having a bottom opening at its front communicating with said fuel tank, a fuel valve including a vertical plunger valve in said compartment at its front and receiving fuel through said opening, said plunger valve being movable between an upper valve opening position and a lower valve closing position, said top wall having a top wall front opening overlying said valve for flow out of said casing of fuel vapors from said valve;

a first lever extending longitudinally in said compartment, lateral pivot means mounting said first lever to said casing intermediate the ends of said first lever, means coupling the front end of said first lever to said plunger for movement thereof in the opposite sense to movement of the rear end of said first lever, spring means coupling the rear end of said first lever and said casing and urging said rear end upwardly so as to maintain said valve normally closed;

a snuffer, shaped and sized to block said top wall front opening and thereby block raising of said plunger, lateral pivot means mounting said snuffer on said casing above said top wall for movement between top wall front opening blocking and unblocking positions, a second lever, means mounting said second lever on said casing above said top wall for movement between first and second positions, means coupling said second lever and said snuffer for movement of said snuffer to blocking position by movement of said second lever to first position and to unblocking position by movement of said second lever to second position;

said top wall having a rear opening, means including a member extending through said top wall rear opening coupling said second lever and said first lever so that movement of said second lever to second position causes lowering of the rear end of said first lever, whereby said first lever positively moves said plunger valve between said valve opening and valve closing positions, and means biasing said second lever to first position.

2. Cigarette lighter mechanism according to claim 1, said means mounting said second lever on said casing comprising lateral pivot means at the rear of said second lever, the front of said second lever being raised from said top wall in its first position and lowered towards said top wall in its second position, said means coupling said first and second levers comprising a third lever in said compartment laterally pivoted to said casing behind said first lever and extending over and abutting the rear end of said first lever, said third lever having a transverse extension extending through said top wall rear opening and abutting the bottom of said second lever forwardly of its pivot.

3. Cigarette lighter mechanism according to claim 1, said means mounting said second lever on said casing comprising lateral pivot means coupling the front of said second lever to said snuffer at a point located above the snuffer pivot in the first position of said second lever and behind the snuffer pivot in the second position of said second lever corresponding to rearward movement thereof, said means coupling said first and second levers comprising a transverse extension in the rear end of said first lever extending upwardly through said top wall rear opening, a cam, means mounting said cam on the rear end of said second lever, the upper end of said extension abutting the bottom of said cam, the bottom of said cam being shaped to lower said extension by reason of rearward movement of said second lever to second position, said means biasing said second lever to first position comprising a second spring connecting said second lever and said top wall.

4. Cigarette lighter mechanism according to claim 3, said cam being a third lever mounted by lateral pivot upon the rear end of said second lever, said casing having a bracket on its top wall, said brackets longitudinally slidably receiving the free end of said cam lever and limiting its forward movement, said second lever being downwardly rearwardly movement with resulting lowering of the pivot of said cam lever and further resulting lowering of its cam surface against the upper end of said first lever extension so as to lower the rear end of said first lever.
